(57) **ABSTRACT**

A display device includes a backlight device, and a backlight control circuit. The backlight device includes a plurality of light sources configured to illuminate a plurality of zones of a display panel, respectively. The zones are aligned in a first direction, and each zone includes a plurality of subzones aligned in a second direction perpendicular to the first direction. The backlight control circuit is configured to receive an input image and determine a backlight value for a target light source of the light sources, the target light source corresponding to a target zone of the plurality of zones. Determining the backlight value for the target light source includes: determining local brightness values of respective subzones of the target zone based on the input image; and determining the backlight value for the target light source based on the local brightness values of the subzones of the target zone.

**LOCAL DIMMING FOR PANEL DISPLAY
DEVICES USING ONE-DIMENSIONAL (1D)
LIGHT SOURCE ARRAY**

TECHNICAL FIELD

This disclosure relates generally to panel display devices, and more particularly to local dimming for panel display devices using a one-dimensional (1D) light source array.

BACKGROUND

Panel display devices with a light-transmissive display panel (e.g., a light-transmissive liquid crystal display (LCD) panel) may incorporate a backlight device that illuminates the light-transmissive display panel. Modern backlight devices, such as direct-lit backlights, full-array backlights etc., may be configured to illuminate a display panel with a two-dimensional (2D) array of light sources (e.g., light-emitting diodes (LEDs)). The use of a 2D light source array in a backlight device enables the implementation of a local dimming function that can achieve high dynamic contrast and low power consumption by individually controlling the respective light sources of the 2D light source array according to input image data.

The use of a 2D light source array in a panel display device may however undesirably increase the volume of the panel display device, because the use of the 2D light source array, which is provided behind the display panel, inevitably increases the thickness of the panel display device. Accordingly, it would be advantageous to provide a technology capable of implementing a local dimming function with a reduced volume of the panel display device.

SUMMARY

This summary is provided to introduce a selection of concepts in a simplified form that are further described below. This summary is not necessarily intended to identify key features or essential features of the present disclosure. The present disclosure may include the following various aspects and embodiments.

In an exemplary embodiment, the present disclosure provides a display device that includes a display panel, a backlight device, and a backlight control circuit. The backlight device includes a plurality of light sources configured to illuminate a plurality of zones of the display panel, respectively. The plurality of zones are aligned in a first direction, and each of the plurality of zones includes a plurality of subzones aligned in a second direction perpendicular to the first direction. The backlight control circuit is configured to receive an input image and determine a backlight value for a target light source of the plurality of light sources, the target light source corresponding to a target zone of the plurality of zones. Determining the backlight value for the target light source includes: determining local brightness values of respective subzones of the target zone based on the input image; and determining the backlight value for the target light source based on the local brightness values of the subzones of the target zone.

In another exemplary embodiment, the present disclosure provides a display driver that includes a driver circuit and a backlight control circuit. The driver circuit is configured to drive a display panel based on an input image. The display panel is illuminated by a backlight device that includes a plurality of light sources aligned in a first direction and configured to illuminate a plurality of zones of the display

2

panel, respectively. Each of the plurality of zones includes a plurality of subzones aligned in a second direction perpendicular to the first direction. The backlight control circuit is configured to determine a backlight value for a target light source of the plurality of light sources, the target light source corresponding to a target zone of the plurality of zones. Determining the backlight value for the target light source includes: determining local brightness values of the respective subzones of the target zone based on the input image; and determining the backlight value for the target light source based on the local brightness values of the subzones of the target zone.

In yet another exemplary embodiment, the present disclosure provides a method. A method includes illuminating, by a backlight device including a plurality of light sources, a plurality of zones of a display panel, respectively. The plurality of zones is aligned in a first direction, each of the plurality of zones including a plurality of subzones aligned in a second direction perpendicular to the first direction. The method further includes receiving an input image and determining a backlight value for a target light source of the plurality of light sources, the target light source corresponding to a target zone of the plurality of zones. Determining the backlight value for the target light source includes: determining local brightness values of the respective subzones of the target zone based on the input image; and determining the backlight value for the target light source based on the local brightness values of the subzones of the target zone.

Other features and aspects are described in more detail below with reference to the attached drawings.

BRIEF DESCRIPTION OF THE DRAWINGS

FIG. 1 shows an example configuration of a panel display device, according to one or more embodiments.

FIG. 2 shows an example arrangement of zones of a display panel, according to one or more embodiments.

FIGS. 3A and 3B show example relationships between input images and backlight values of respective light sources.

FIGS. 4A and 4B show an example process for determining backlight values for respective light sources.

FIGS. 5A, 5B, and 5C show an example process for determining backlight values for respective light sources while an image element is moving.

FIG. 6 shows an example configuration of a display driver, according to one or more embodiments.

FIG. 7 is a flowchart showing an example process for determining backlight values for respective light sources, according to one or more embodiments.

FIG. 8 is a flowchart showing an example process for determining local brightness values of respective subzones, according to one or more embodiments.

FIG. 9A shows an example selection of a target part of an input image for a subzone of interest, according to one or more embodiments.

FIG. 9B shows example filter coefficients defined for pixels of the target part for the subzone of interest shown in FIG. 9A, according to one or more embodiments.

FIG. 10 shows an example of image processing performed in an image analysis circuit, according to one or more embodiments.

FIGS. 11A, 11B, and 11C show an example process for determining backlight values for respective light sources while an image element is moving, according to one or more embodiments.

FIG. 12 shows an example configuration of a display driver, according to other embodiments.

FIG. 13 shows an example configuration of a 1D module, according to one or more embodiments.

FIG. 14 is a timing diagram showing an example operation of the 1D module shown in FIG. 13, according to one or more embodiments.

FIG. 15 shows an example configuration of a display device adapted for a local dimming function based on a 2D light source array, according to one or more embodiments.

FIG. 16 shows a side view configuration of the display device shown in FIG. 15, according to one or more embodiments.

FIG. 17 shows an example arrangement of light sources of a 2D backlight device, according to one or more embodiments.

FIG. 18 shows an example configuration of a display driver, according to one or more embodiments.

FIG. 19 shows an example configuration of a 1D module, according to one or more embodiments.

For ease of understanding, where possible, identical reference numerals have been used to designate elements that are common to the figures. It is contemplated that elements disclosed in one embodiment may be utilized in other embodiments without specific recitation. Suffixes may be appended to reference numerals to distinguish elements from one another. The drawings referenced herein are not to be construed as being drawn to scale unless specifically noted. In addition, the drawings are often simplified and details or components are omitted for clarity of presentation and explanation. The drawings and discussion are intended to explain principles discussed below.

DETAILED DESCRIPTION

The following detailed description is exemplary in nature and is not intended to limit the disclosure or the applications and uses of the disclosure. Further, there is no intention to be bound by any expressed or implied theory presented in the preceding background, summary and brief description of the drawings, or in the following detailed description.

In the following detailed description, numerous specific details are set forth in order to provide a more thorough understanding of the disclosed technology. However, it will be apparent to one of ordinary skill in the art that the disclosed technology may be practiced without these specific details. In other instances, well-known features have not been described in detail so as not to unnecessarily complicate the description.

The term “coupled” as used herein means connected directly to or connected through one or more intervening components or circuits. Further, throughout the application, ordinal numbers (e.g., first, second, third, etc.) may be used as an adjective for an element (i.e., any noun in the application). The use of ordinal numbers is not to imply or create any particular ordering of the elements nor to limit any element to being only a single element unless expressly disclosed, such as by the use of the terms “before”, “after”, “single”, and other such terminology. Rather, the use of ordinal numbers is to distinguish between the elements. By way of an example, a first element is distinct from a second element, and the first element may encompass more than one element and succeed (or precede) the second element in an ordering of elements.

As discussed above, a modern backlighting system, such as a direct-lit backlight, a full-array backlight etc., may be configured to illuminate a display panel with a two-dimen-

sional (2D) array of light sources (e.g., light emitting diodes (LEDs)) to achieve a local dimming function, which can realize high dynamic contrast by individually controlling the respective light sources of the 2D light source array according to input image data. The use of a 2D light source array in a panel display device may however undesirably increase the volume of the panel display device, because the 2D light source array, which is provided behind the display panel, inevitably increases the thickness of the panel display device.

The present disclosure recognizes that the local dimming function can be implemented in an edge-lit panel display device that uses a one-dimensional (1D) light source array configured to illuminate the display panel from its edge. The use of the edge lighting configuration to illuminate the display panel may enable a reduction in the thickness of the panel display system, thereby facilitating a reduction in the volume of the panel display system. The local dimming function based on a 1D light source array may however raise different issues than that based on a 2D light source array. The following describes various embodiments for appropriately controlling the brightness levels of light sources of a 1D light source array to achieve the local dimming function in an edge-lit panel display device.

FIG. 1 shows an example configuration of an edge-lit panel display device 1000, according to one or more embodiments. In the shown embodiment, the panel display device 1000 includes a display panel 100 and a 1D backlight device 200. The display panel 100 may be a light-transmissive display panel such as a liquid crystal display (LCD) panel. The 1D backlight device 200 includes a 1D array of light sources 210 and a light diffusion plate 250 that has a major surface attached to the rear surface of the display panel 100. The light sources 210 are aligned in a given direction (the vertical direction in FIG. 1) and coupled to a side surface 250a of the light diffusion plate 250. The light sources 210 may each include one or more light emitting diodes (LEDs) or other types of light emitting elements. Light beams emitted from the light sources 210 enter the side surface of the light diffusion plate 250 and spread across the major surface of the light diffusion plate 250 to illuminate the display panel 100.

The brightness levels of the respective light sources 210 of the 1D backlight device 200 may be determined based on “zones” defined by segmenting the display panel 100. In one or more embodiments, “zones” of the display panel 100 are defined for the respective light sources 210 such that the “zones” are respectively illuminated by the light sources 210. To achieve the local dimming function, the brightness levels of the respective light sources 210 may be controlled based on average picture levels (APLs) of images displayed in the corresponding zones.

FIG. 2 shows an example arrangement of zones 110 of the display panel 100, according to one or more embodiments. It is noted that directions may be indicated using a Cartesian XY coordinate system, where the X axis is oriented in the horizontal direction of the display panel 100 and the Y axis is oriented in the vertical direction of the display panel 100. The zones 110 are defined such that the respective light sources 210 illuminate the corresponding zones 110. In the shown embodiment, the zones 110 are vertically aligned (or aligned in a first direction) and the horizontal width of each zone 110 is the same as the horizontal width of the display panel 100. The zones 110 have a substantially rectangular shape extending in the horizontal direction (or a second direction perpendicular to the first direction). The light sources 210 are each configured to emit light in the hori-

zontal direction (or the second direction) to illuminate the entirety of the corresponding zone **110**. It should be noted that due to the light diffusion characteristics of the light sources **210**, each light source **210** primarily illuminates the corresponding zone **110**, but may secondarily illuminate at least portions of the zones **110** adjacent to the corresponding zone **110**.

Since the horizontal width of each zone **110** is the same as the horizontal width of the display panel **100**, the vertical dimension (or vertical height) of each zone **110** is different from the horizontal dimension (or horizontal width) of each zone **110**. In the embodiment shown in FIG. 2, each zone **110** is defined to be longer horizontally than vertically. In implementations where the brightness levels of the respective light sources **210** are controlled based on average picture levels (APLs) of images displayed in the corresponding zones **110**, the difference between the vertical and horizontal dimensions of each zone **110** may cause undesirable changes in the brightness levels of image elements contained in the displayed image depending on the vertical and horizontal dimensions of the image elements.

FIG. 3A shows an example relationship between an input image and backlight values of the respective light sources **210**, according to one or more examples of the present disclosure. It is noted that in FIG. 3A (and in the following figures), suffixes from one to eight are appended to the numerals “110” to distinguish the zones **110** from one another. In the shown example, the input image includes an image element **510** with the highest specified luminance level (indicated by the black color) in a background with the lowest specified luminance level (indicated by the white color). The image element **510** is an oblique line traversing the zones **1101** to **1108**, where the vertical dimension of the image element **510** is greater than the horizontal dimension.

In one implementation, to achieve the local dimming function, the backlight values of the respective light sources **210** may be determined based on the APLs of the corresponding zones **110**. The backlight value referred to herein may be a value that indicates the brightness level to which the light source **210** of interest is to be controlled. In the example shown in FIG. 3A, the backlight values of all of the light sources **210** are commonly determined to be the same value, e.g., “10”, since the APLs of the zones **1101** to **1108** are the same.

FIG. 3B shows another example relationship between an input image that includes an image element **520** and backlight values of the respective light sources **210**, according to one or more examples of the present disclosure. In the shown example, the input image includes an image element **520** with the highest specified luminance level (indicated by the black color) in a background with the lowest specified luminance level (indicated by the white color). The image element **520** is a figure obtained by rotating the image element **510** shown in FIG. 3A by 90 degrees. Accordingly, the vertical dimension of the image element **520** is the same as the horizontal dimension of the image element **510** and the horizontal dimension of the image element **520** is the same as the vertical dimension of the image element **510**. The entirety of the image element **520** is located in the zone **1101**.

In one implementation, the backlight values of the respective light sources **210** may be determined based on the APLs of the corresponding zones **110** as is the case with FIG. 3A. In this case, the backlight values of the light sources **210** corresponding to the zones **1102** to **1108** are determined to be zero, while the backlight value of the light source **210** corresponding to the zone **1101** is determined to be a

non-zero value “80” because the APL of the zone **1101** for the case of FIG. 3B is eight times the APL of the zones **1101** to **1108** for the case of FIG. 3A. Accordingly, the actual luminance of the image element **520** will be different from that of the image element **510**. The results shown in FIGS. 3A and 3B imply that determining the backlight values of the respective light sources **210** based on the APLs of the corresponding zones **110** may cause undesirable changes in the luminance of image elements depending on the vertical and horizontal dimensions of the image elements.

The present disclosure recognizes that the undesirable changes of image elements depending on the vertical and horizontal dimensions of the image elements result from the fact that the aspect ratio of the zones **110** is large. The aspect ratio referred to herein is the ratio of the larger of the horizontal width and vertical height of the zones **110** to the smaller of the horizontal width and vertical height. For example, in the zone arrangement shown in FIG. 2, the horizontal width of the zones **110** is much larger than the vertical height of the zones **110**, and therefore the aspect ratio of the zones **110** is much larger than one. Due to the large aspect ratio of the zones **110**, image elements oriented in different directions result in different backlight values of the light sources **210**, causing an undesirable luminance difference of the image elements. This may undesirably deteriorate the image quality. In the following, various embodiments are presented which achieve improved image quality in panel display devices based on 1D backlight devices.

In one or more embodiments, to address undesirable changes in the luminance of image elements depending on the vertical and horizontal dimensions of the image elements, the backlight values of the respective light sources **210** may be determined based on “subzones” **120** defined by segmenting each zone **110** such that the subzones **120** have a substantially rectangular shape. In one or more embodiments, the aspect ratio of the subzones **120** is closer to one than the aspect ratio of the zones **110** as shown in FIGS. 4A and 4B. In one implementation, the subzones **120** have a substantially square shape. The use of the subzones **120** with an aspect ratio equal to or close to one may effectively mitigate undesirable changes in the luminance of image elements depending on the vertical and horizontal dimensions of the image elements. In the shown embodiment, each zone **110** contains 12 horizontally aligned subzones **120**. In other embodiments, each zone **110** may contain fewer or more than 12 horizontally aligned subzones **120**.

In one or more embodiments, the backlight value of a light source **210** of interest may be determined as follows. The APLs of the subzones **120** of the zone **110** corresponding to the light source **210** of interest may first be calculated, and the maximum APL for that zone **110**, i.e., the maximum value of the APLs of the subzones **120** of that zone **110**, may then be determined. The backlight value of the light source **210** of interest may be determined based on the maximum APL of the zone **110** corresponding to that light source **210**. In one implementation, the backlight value of the light source **210** of interest may be determined to be proportional to the maximum APL of the corresponding zone **110**.

FIG. 4A shows examples of the maximum APLs of the respective zones **110** and the backlight values determined for the respective light sources **210** for the input image containing the image element **510**, according to one or more examples of the present disclosure. In the shown example, the image element **510** is located in the leftmost column of the subzones **120**. The APLs of the leftmost subzones **120** of the respective zones **110** are calculated as “10”, for example,

and the APLs of other subzones **120** are calculated as “0”. Accordingly, the maximum APLs of all zones **110** are determined to be “10”, and the backlight values of all light sources **210** are determined to be “10”. The image element **510** is displayed by the light sources **210** with the backlight value of “10”.

FIG. 4B shows the maximum APLs of the respective zones **110** and the backlight values determined for the respective light sources **210** for the input image containing the image element **520**, according to one or more examples of the present disclosure. In the shown example, the image element **520** is located in the leftmost eight subzones **120** of the zone **1101**. The APLs of the leftmost eight subzones **120** of the zone **1101** are calculated as “10”, for example, and the APLs of other subzones **120** are calculated as “0”. Further, the maximum APL of the zone **1101** is determined as “10”, and the maximum APLs of other zones **1102** to **1108** are determined to be “0”. The backlight value of the light source **210** corresponding to the zone **1101** is determined to be “10” and the backlight values of other light sources **210** are determined to be “0”. Accordingly, the image element **520** is displayed by the light source **210** corresponding to the zone **1101** with the backlight value of “10”. The results shown in FIGS. 4A and 4B indicate that the determination scheme based on the subzones **120** effectively mitigates undesirable changes in the luminance of image elements depending on the vertical and horizontal dimensions of the image elements.

Although the above-described determination scheme based on the subzones **120** effectively mitigates undesirable changes in the luminance of image elements depending on the vertical and horizontal dimensions of the image elements, there is still room to further improve the image quality. More specifically, the above-described scheme based on the subzones **120** may cause an undesirable decrease in the luminance of an image element as the image element moves to cross a boundary between subzones **120**. FIGS. 5A, 5B, and 5C show example changes in the luminance of an image element **530**, according to one or more examples of the present disclosure.

Referring to FIG. 5A, the image element **530** is initially located in the third leftmost column of the subzones **120** of the display panel **100**. In this case, the maximum APLs of all zones **110** are calculated to be “10” and the backlight values of all light sources **210** are determined to be “10”. When the image element **530** crosses the boundaries between the third and fourth columns of the subzones **120** as shown in FIG. 5B, the maximum APLs of one or more of the zones **110** decrease, and therefore the backlight values of one or more of the light sources **210** also decrease. In the example shown in FIG. 5B, the APL of the third leftmost subzone **120** of the zone **1104** is calculated as “8”, and the APL of the fourth leftmost subzone **120** of the zone **1105** is calculated as “9”. Accordingly, the backlight values of the light sources **210** corresponding to the zones **1104** and **1105** are determined to be “8” and “9”, respectively. When the entirety of the image element **530** becomes within the fourth column of the subzones **120** after crossing the boundary between the third and fourth columns of the subzones **120** as shown in FIG. 5C, the maximum APLs of all the zones **110** are calculated as “10” and the backlight values of all the light sources **210** are determined to be “10” as is the case with FIG. 5A. As shown in FIGS. 5A, 5B, and 5C, the movement of the image element **530** to cross the boundary between the third and fourth columns of the subzones **120** may undesirably cause a decrease in the luminance of the image element **530**. In view of this, the following describes various embodiments

for further appropriately determining backlight values for respective light sources of a 1D light source array to achieve a local dimming function in an edge-lit panel display device.

FIG. 6 shows an example configuration of a display driver **300** of the panel display device **1000**, according to one or more embodiments. The display driver **300** is configured to drive or update pixels of the display panel **100** based on input image data received from an external image source. The input image data corresponds to an input image and includes pixel data for the respective pixels of the display panel **100**. The pixel data for a pixel may include graylevels of the respective primary colors (e.g., red, green, and blue) of the pixel. The display driver **300** is further configured to control the light sources **210** of the 1D backlight device **200**.

In the shown embodiment, the display driver **300** includes an image processing circuit **310**, a driver circuit **320**, and a backlight control circuit **330**. The image processing circuit **310** is configured to perform image processing on the input image data to generate processed image data. The image processing performed by the image processing circuit **310** may include color adjustment, demura correction, deburn correction, image scaling, gamma transformation, or other image processing. The driver circuit **320** is configured to drive or update the display panel **100** based on the processed image data.

The backlight control circuit **330** is configured to generate backlight values for the respective light sources **210** of the 1D backlight device **200** to individually control the light sources **210**. The backlight value referred to herein may be a value indicating the brightness level to which the light source **210** of interest is to be controlled. To implement a local dimming function, the backlight control circuit **330** is configured to receive the input image data and determine the backlight values for the respective light sources **210** based on the input image data.

In the shown embodiment, the backlight control circuit **330** includes an image analysis circuit **340**, a 1D random access memory (RAM) **350**, and a backlight value generation circuit **360**. The image analysis circuit **340** is configured to analyze the input image data to generate base backlight values for the respective light sources **210** based on the input image data. The image analysis circuit **340** is further configured to forward the base backlight values to the 1D RAM **350**. The 1D RAM **350** is configured to store the base backlight values received from the image analysis circuit **340**. The backlight value generation circuit **360** is configured to generate the backlight values for the respective light source **210** by modifying the base backlight values based on a display brightness value (DBV). The DBV referred to herein is a value that specifies a desired display brightness level of the panel display device **1000**, wherein the display brightness level referred to herein is the overall brightness level of the display image displayed on the display panel **100**. The DBV may be generated by an external controller based on a user operation. For example, when an instruction to adjust the display brightness level of the panel display device **1000** is manually input to an input device, the DBV may be generated based on this instruction. In one implementation, the backlight value generation circuit **360** may be configured to generate the backlight values for the respective light sources **210** by multiplying the base backlight values by a multiplication factor determined based on the DBV.

In some implementations, to mitigate display mura potentially caused by variations in the characteristics of the light sources **210**, the backlight value generation circuit **360** may be further configured to store demura data and modify the base backlight values for the respective light sources **210**

based on the demura data. The demura data may include demura compensation factors for the respective light sources **210**. In such an implementation, the backlight value generation circuit **360** may be configured to apply the demura compensation factors to the base backlight values for the respective light sources **210** during the determination of the backlight values used to control the respective light sources **210**. The backlight values thus generated are provided to the 1D backlight device **200** and used to control the respective light sources **210**.

FIG. 7 is a flowchart showing an example process **700** for determining the backlight values for the respective light sources **210** by the backlight control circuit **330**, according to one or more embodiments. It will be appreciated that any of the following steps may be performed in any suitable order.

In step **702** of the process **700**, the image analysis circuit **340** of the backlight control circuit **330** determines local brightness values of the respective subzones **120** based on the input image. The “local brightness value” for a subzone **120** of interest, as referred to herein, may be a value representing the brightness of that subzone **120**. In some implementations, the local brightness value for a subzone **120** of interest may represent the brightness of that subzone **120** and also represent the brightness of the region around that subzone **120**.

FIG. 8 is a flowchart showing an example process **800** for determining the local brightness values of the respective subzones **120**, according to one or more embodiments. In one implementation, the process **800** is implemented by the image analysis circuit **340**. It will be appreciated that that any of the following steps may be performed in any suitable order.

In step **802**, the image analysis circuit **340** selects target parts of the input image for the respective subzones **120**. FIG. 9A shows an example selection of a target part of the input image for each subzone **120**, according to one or more embodiments. In FIG. 9A, the numeral “**120a**” denotes a subzone **120** of interest and the numerals “**120b**” denote the eight subzones **120** adjacent to the subzone **120a** of interest. The numerals “**130**” denote the centers (e.g., the geometric centers) of the subzones **120**. The numeral “**130a**” denotes the center (e.g., the geometric center) of the subzone **120a** of interest, and the numerals “**130b**” denote the centers (e.g., the geometric centers) of the subzones **120b** adjacent to the subzone **120a** of interest.

In one or more embodiments, the target part of the input image for the subzone **120a** of interest is selected such that the target part is displayed in a corresponding region **140a** of the display panel **100**, wherein the corresponding region **140a** is a substantially square region having a boundary that passes the centers of the eight subzones **120b** adjacent to the subzone **120a** of interest. The centers of four of the eight adjacent subzones **120b** are at the four corners of the corresponding region **140a** and the centers of the other four adjacent subzones **120b** are on the four edges of the corresponding region **140a**. The target parts of the input image for other subzones **120** may be selected in a manner similar to the target part for the subzone **120a**. The target part for each subzone **120** may be selected differently, as long as the region of the display panel **100** in which the target part selected for each subzone **120** is displayed incorporates at least that subzone **120**. It should be noted that target parts of the input image for adjacent subzones **120** may overlap. In the example shown in FIG. 9A, the height and width of each target part are both twice the height and width of a subzone

120, and the target part for the subzone **120a** partially overlaps with target parts of its adjacent subzones **120b**.

Referring back to FIG. 8, in step **804**, the image analysis circuit **340** filters the target parts of the input image for the respective subzones **120** to generate filtered image parts for the respective subzones **120**. In one or more embodiments, the filtering is based on a filter that include filter coefficients defined for the respective pixels of the target part of the input image, and the filtered image part is generated by applying the filter coefficients to pixel data of the respective pixels of the target part. In one implementation, the pixel data of the respective pixels of the filtered image part may be generated by multiplying the pixel data of the corresponding pixels of the target part by the filter coefficients defined for the corresponding pixels of the target part.

FIG. 9B shows example filter coefficients defined for the pixels of the target part for the subzone **120a**, according to one or more embodiments, wherein the numeral “**150a**” denotes the target part for the subzone **120a**. Shown in FIG. 9B is a part of the input image that includes the target part **150** for the subzone **120a**. The numeral **130a** denotes the center of the subzone **120a**, and the numerals **130b** denote the corresponding center positions of the adjacent subzones **120b** in the input image. It is noted that the outer boundary of the target part **150a** for the subzone **120a** coincides with the boundary of the corresponding region **140a** for the subzone **120a** shown in FIG. 9A.

The filter coefficients defined for the pixels of the target part for the subzone **120a** depend on the respective distances between the pixels of the target part of the input image and the center of the subzone **120a** in the input image. In one implementation, the filter coefficients defined for the pixels of the target part for the subzone **120a** increase as the respective distances between the pixels of the target part of the input image and the center of the subzone **120a** in the input image decrease. In the shown embodiment, the filter coefficient for the pixel positioned at the center of the subzone **120a** is W_1 (e.g., 1.0), which is the maximum filter coefficient, and the filter coefficients for the pixels positioned at the outer boundary of the target part **150a** are zero. The filter coefficients defined for other pixels of the target part for the subzone **120a** are values between zero and W_1 . The filter coefficients thus defined are applied to the pixel data of the respective pixels of the target part to generate the filtered image part. The filter coefficients for the pixels of other target parts for other subzones **120** may be defined in a manner similar to the filter coefficients defined for the pixels of the target part for the subzone **120a** as shown in FIG. 9B.

Referring back to FIG. 8, in step **806**, the image analysis circuit **340** analyzes the filtered image parts generated for the respective subzones **120** to determine the local brightness values of the respective subzones **120** based on the APLs of the filtered image parts. The APL of a filtered image part, which may also be referred to as the filtered image local APL, is the average of the pixel luminance levels of the filtered image part. In one implementation, the local brightness value for a subzone **120** is determined to be the same as the APL of the filtered image part generated for that subzone **120**. Alternatively, the local brightness value for a subzone **120** may be determined by performing an arithmetic operation (e.g., multiplication, division, addition, subtraction etc.) on the APL of the filtered image part generated for that subzone **120**.

FIG. 10 shows a summary of the image processing performed in the image analysis circuit **340**, according to one or more embodiments. The image analysis circuit **340** is

11

configured to first select the target part of the input image for each subzone **120**. As discussed above, the target part of the input image for each subzone **120** is selected such that the target part is displayed in the corresponding region **140a** of the display panel **100**, as described in relation to FIG. 9A. The image analysis circuit **340** is further configured to apply a filter to the target part selected for each subzone **120** to generate the filtered image part. The filter may have the filter coefficients defined as shown in FIG. 9B. The image analysis circuit **340** is further configured to determine the local brightness values of the respective subzones **120** based on the APLs of the filtered image parts generated for the respective subzones **120**.

In other embodiments, the local brightness values of the respective subzones **120** may be determined to be the APLs of the subzones **120** calculated based on the input image data. Using the APLs of the subzones **120** as the local brightness values of the respective subzones **120** may however cause undesired changes in the brightness of the displayed image when an image element (or an object) with a high specified luminance level (e.g., the highest specified luminance level) moves in the vertical direction to cross the boundary between adjacent zones **110**, which may be observed as flickering of the displayed image. By using the filtered image parts to determine the local brightness values of the respective subzones **120** as described above, such undesired changes that may occur when an image element with a high specified luminance level moves in the vertical direction may be effectively mitigated.

Referring back to FIG. 7, after determining the local brightness values of the respective subzones **120** in step **702**, the image analysis circuit **340** averages the local brightness values determined for respective combinations of two or more adjacent ones of the subzones **120** in each zone **110** to determine averaged local brightness values for each zone **110** in step **704**. FIGS. 11A, 11B, and 11C show an example of the averaging of the local brightness values, according to one or more embodiments. In the examples shown in FIGS. 11A, 11B, and 11C, the local brightness values are averaged with respect to respective combinations of two adjacent subzones **120** in each zone **110** to determine averaged local brightness values for that zone **110**. In this case, the number of the averaged local brightness values for each zone **110** is less than the number of the subzones **120** in each zone **110** by one. For example, in implementations where the number of the subzones **120** in each zone **110** is 12, the number of the averaged local brightness values calculated for each zone **110** is 11.

In the example shown in FIG. 11A, the local brightness values of the five leftmost subzones **120** in the zone **1101** are calculated as 0.0, 6.7, 13.3, 6.7, and 0.0, respectively, and four averaged local brightness values are determined for the five leftmost subzones **120**. The averaged local brightness value for the leftmost and second leftmost subzones **120** in the zone **1101** is calculated to be 3.4, which is almost equal to $(0.0+6.7)/2$. The averaged local brightness value for the second leftmost and third leftmost subzones **120** in the zone **1101** is calculated to be 10.0, which is almost equal to $(6.7+13.3)/2$. The averaged local brightness values for other combinations of two adjacent subzones **120** in the zone **1101** are calculated in a similar manner. Further, the averaged local brightness values for other zones **110** are calculated similarly to the averaged local brightness values for the zone **1101**. In alternative implementations, the averaging of the local brightness values may be implemented for respective

12

combinations of three or more adjacent ones of the subzones **120** in each zone **110** to determine averaged local brightness values for each zone **110**.

Referring back to FIG. 7, in step **706**, the image analysis circuit **340** determines the maximum value of the averaged local brightness values for each zone **110**. The columns “MAX” in FIGS. 11A, 11B, and 11C respectively show examples of the determined maximum values of the averaged local brightness values for the respective zones **110**.

10 In step **708**, the image analysis circuit **340** further determines the base backlight value for each light source **210** based on the maximum value of the averaged local brightness values determined for the zone **110** corresponding to that light source **210**. In one implementation, the image analysis circuit **340** determines the base backlight value for each light source **210** such that the base backlight value for a light source **210** of interest increases as the maximum value of the averaged local brightness values determined for the zone **110** corresponding to that light source **210** increases. The base backlight values determined for the respective light sources **210** are forwarded and stored in the 1D RAM **350** (shown in FIG. 6).

15 In step **710**, the backlight value generation circuit **360** receives the base backlight values for the respective light sources **210** from the 1D RAM **350** and determine the backlight value for each light source **210** based on the base backlight value for each light source **210** and the display brightness value (DBV). In one implementation, the backlight value generation circuit **360** generates the backlight values for the respective light sources **210** by modifying the base backlight values based on the DBV. As described above, the DBV is a value that specifies a desired display brightness level of the panel display device **1000**. In one implementation, the backlight value generation circuit **360** 20 may be configured to generate the backlight values for the respective light sources **210** by multiplying the base backlight values by a multiplication factor determined based on the DBV. The backlight values thus generated are provided to the 1D backlight device **200** and used to control the respective light sources **210**.

25 The right parts of FIGS. 11A, 11B, and 11C show an example result of determining the backlight values for the light sources **210** by the above-described process **700** in implementations where the input image containing the image element **530** is displayed, according to one or more embodiments. In the implementation shown in FIGS. 11A, 11B, and 11C, similarly to the case shown in FIGS. 5A, 5B, 5C, the image element **530** is initially located in the third leftmost column of the subzones **120** of the display panel **100** and is then moved to the interior of the fourth leftmost column of the subzones **120** after crossing the boundaries between the third and fourth columns of the subzones **120**. As shown in FIGS. 11A, 11B, and 11C, the process **700** for determining the backlight values for the respective light sources **210** results in the maximum APLs of all the zones **110** being kept constant at “10” during the movement of the image element **530**, thereby mitigating an undesirable decrease in the luminance of the image element **530**.

30 FIG. 12 shows an example configuration of a display driver **1300** of the panel display device **1000**, according to other embodiments. The display driver **1300** is configured similarly to the display driver **300** shown in FIG. 6, except that the display driver **1300** includes a backlight control circuit **1330** instead of the backlight control circuit **330**. The 35 backlight control circuit **1330** includes an image analysis circuit **1340**, a 2D RAM **1350**, a 1D module **1360**, and a backlight value generation circuit **1370**. The image analysis

circuit 1340 is configured to analyze the input image data to generate local brightness values of the respective subzones 120. The process 800 described in relation to FIG. 8 may be used to generate the local brightness values of the respective subzones 120. The image analysis circuit 1340 is further configured to forward the local brightness values generated for the respective subzones 120 to the 2D RAM 1350. The 2D RAM 1350 is configured to store the local brightness values generated for the respective subzones 120 and sequentially forward the stored local brightness values to the 1D module 1360. The 1D module 1360 is configured to generate the base backlight values for the respective light sources 210 based on the local brightness values stored in the 2D RAM 1350. The base backlight values for the respective light sources 210 may be generated by implementing steps 704, 706, and 708 of the process 700 described in relation to FIG. 7. The backlight value generation circuit 1370 may be configured to generate the backlight values for the respective light source 210 by modifying the base backlight values based on the DBV. In implementations where the backlight value generation circuit 1370 stores demura data, the backlight value generation circuit 1370 may be configured to modify the base backlight values for the respective light sources 210 further based on the demura data to mitigate display mura.

FIG. 13 shows an example configuration of the 1D module 1360, according to one or more embodiments. In the shown embodiment, the 1D module 1360 includes a flipflop FF0 1361, a flipflop FF1 1362, an averaging circuit 1363, a flipflop FF2 1364, a maximum value circuit 1365, and a flipflop FF3 1366. The flipflop FF0 1361 has a data input configured to sequentially receive the local brightness values from the 2D RAM 1350 and the flipflop FF1 1362 has a data input coupled to the data output of the flipflop FF0 1361 and is configured to output the local brightness values received from the flipflop FF0 1361 with a delay of one operation cycle (e.g., one clock cycle). The data outputs of the flipflops FF0 1361 and FF1 1362 are coupled to the inputs of averaging circuit 1363. The averaging circuit 1363 is configured to calculate the average of the local brightness values received from the flipflops FF0 1361 and FF1 1362. The flipflop FF2 1364 is configured to latch the output of the averaging circuit 1363 and forward the same to the maximum value circuit 1365. The maximum value circuit 1365 is configured to output a larger one of the outputs of the flipflop FF2 1364 and the flipflop FF3 1366. The flipflop FF3 1366 is configured to latch the output of the maximum value circuit 1365.

The 1D module 1360 thus configured sequentially receives and processes the local brightness values of the respective subzones 120 of each zone 110 to determine the base backlight value of the light source 210 corresponding to that zone 110. When the processing for determining the local brightness values of the subzones 120 of each zone 110 is completed, the output of the flipflop FF3 is the maximum value of the averaged local brightness values calculated for that zone 110, which is used as the base backlight value for the light source 210 corresponding to that zone 110, as described in detail below.

FIG. 14 is a timing diagram showing an example operation of the 1D module 1360 in processing the local brightness values of respective subzones 120 for each zone 110, according to one or more embodiments. In FIG. 14, B[i] denotes the local brightness value of the i-th leftmost subzone 120 of the zone 110 of interest, and "#i" denotes the i-th operation cycle (e.g., i-th clock cycle) in the processing

for the zone 110 of interest. Initially, the value "m" stored in the flipflop FF3 1366 is zero.

During operation cycle #1, the 2D RAM 1350 outputs the local brightness value B[1] of the leftmost subzone 120. During operation cycle #2, the flipflop FF0 1361 latches the local brightness value B[1] from the 2D RAM 1350 while the 2D RAM 1350 outputs the local brightness value B[2] of the second leftmost subzone 120. During operation cycle #3, the flipflop FF1 1362 latches the local brightness value B[1] from the flipflop FF0 1361 and the flipflop FF0 1361 latches the local brightness value B[2] from the 2D RAM 1350, while the 2D RAM 1350 outputs the local brightness value B[3] of the third leftmost subzone 120.

During operation cycle #4, the averaging circuit 1363 calculates the average Bave[1] of the local brightness values B[1] and B[2]. Meanwhile, the flipflop FF1 1362 latches the local brightness value B[2] from the flipflop FF0 1361, and the flipflop FF0 1361 latches the local brightness value B[3] from the 2D RAM 1350, while the 2D RAM 1350 outputs the local brightness value B[4] of the fourth leftmost subzone 120.

During operation cycle #5, the maximum value circuit 1365 outputs a larger one of the output of the averaging circuit 1363 (i.e., the average Bave[1] of the local brightness values B[1] and B[2]) and the value "m" stored in the flipflop FF3 1366, and the value "m" stored in the flipflop FF3 1366 is updated with the output of the maximum value circuit 1365. Meanwhile, the averaging circuit 1363 calculates the average Bave[2] of the local brightness values B[2] and B[3]. Further, the flipflop FF1 1362 latches the local brightness value B[3] from the flipflop FF0 1361, and the flipflop FF0 1361 latches the local brightness value B[4] from the 2D RAM 1350, while the 2D RAM 1350 outputs the local brightness value B[5] of the fifth leftmost subzone 120.

During subsequent operation cycles, a similar process to that performed during operation cycle #5 is repeated. The process is repeated until the maximum value of the averaged local brightness values is obtained at the output of the flipflop FF3 1366.

The 1D module 1360 of the embodiment shown in FIG. 13 is configured to generate the averaged local brightness values for each zone 110 by averaging the local brightness values determined for respective combinations of two adjacent subzones 120 in that zone 110. In alternative embodiments, the 1D module 1360 may be configured to generate averaged local brightness values for each zone 110 by averaging the local brightness values determined for respective combinations of three or more adjacent subzones 120 in that zone 110. In such embodiments, the 1D module 1360 may include one or more additional flipflops serially coupled to the output of the flipflop FF1 1362, and the output(s) of the additional flipflop(s) may be coupled to the averaging circuit 1363.

While the display driver 1300 shown in FIG. 12 is configured to implement a local dimming function for the 1D backlight device 200 (shown in FIGS. 1 and 2), in alternative embodiments, a display driver may be configured to be capable of implementing a local dimming function for both a 1D backlight device and a 2D backlight device. The 2D backlight device referred to herein is a backlight device that includes a 2D light source array in which light sources are arranged in rows and columns. The display driver configuration adapted to both of the 1D backlight device and the 2D backlight device allows the display driver to be used in a larger number of display device products, effectively improving the usability of the display driver. The following

describes an example configuration of a display device that includes a 2D backlight device and an example configuration of a display driver configured to be adaptable to both a 1D backlight device and a 2D backlight device.

FIG. 15 shows an example configuration of a panel display device 2000 adapted for a local dimming function based on a 2D light source array, according to one or more embodiments. The panel display device 2000 includes a display panel 2100 and a two-dimensional (2D) backlight device 2200 configured to illuminate the display panel 2100. The display panel 2100 may be a light-transmissive display panel such as a liquid crystal display (LCD) panel. The 2D backlight device 2200 includes a 2D array of light sources 2210. Each light source 2210 may include one or more LEDs or different types of light sources. It is noted that the light sources 2210 are shown in phantom in FIG. 15 because the light sources 2210 are located behind the display panel 2100 as shown in FIG. 16, which shows a side view configuration of the panel display device 2000. While 64 light sources 2210 are shown in FIG. 15, those skilled in the art would appreciate that the 2D backlight device 2200 may include more or less than 64 light sources 2210.

FIG. 17 shows an example arrangement of the light sources 2210 of the 2D backlight device 2200, according to one or more embodiments. In the shown embodiment, the display panel 2100 is segmented into zones 2110 arranged in rows and columns, and the light sources 2210 are located behind the corresponding zones 2110, respectively. The zones 2110 may be substantially rectangular. In one or more embodiments, the zones 2110 has a substantially square shape to reduce the aspect ratio of the zones 2110. Each light source 2210 is arranged such that the projection of each light source 2210 onto the display panel 2100 is positioned at the center (e.g., the geometric center) of the corresponding one of the zones 2110. As used herein, the “corresponding zone” 2110 of a light source 2210 refers to the zone 2110 that includes the projection of that light source 2210 onto the display panel 2100. It should be noted that due to the light diffusion characteristics of the light sources 2210, each light source 2210 primarily illuminates the corresponding zone 2110, but may secondarily illuminate at least portions of the zones 2110 around (e.g., adjacent to) the corresponding zone 2110.

FIG. 18 shows an example configuration of a display driver 2300 configured to be adapted to both the 1D backlight device 200 (shown in FIGS. 1 and 2) and the 2D backlight device 2200 (shown in FIGS. 15 and 16), according to one or more embodiments. The display driver 2300 is configured similarly to the display driver 1300 shown in FIG. 12, except that the display driver 2300 includes a backlight control circuit 2330 instead of the backlight control circuit 1330.

The backlight control circuit 2330 includes an image analysis circuit 2340, a 2D RAM 2350, a 1D module 2360, and a backlight value generation circuit 2370. The image analysis circuit 2340 is configured to generate, based on the input image data, the local brightness values of the respective subzones 120 of the display panel 100 when the display driver 2300 is used in the panel display device 1000 that includes the 1D backlight device 200. The image analysis circuit 2340 is further configured to generate, based on the input image data, local brightness values of the respective zones 2110 of the display panel 2100 when the display driver 2300 is used in the panel display device 2000 that includes the 2D backlight device 2200. In one or more embodiments, the local brightness values of the respective zones 2110 of the display panel 2100 are generated by a process similar to

the process 800 of generating the local brightness values of the subzones 120 of the display panel 100 shown in FIG. 8. In one implementation, the image analysis circuit 2340 is configured to select target parts of the input image for the respective zones 2110 in a manner similar to that performed in step 802 of the process 800 and to filter the target parts to generate filtered image parts for the respective zones 2110 in a manner similar to that performed in step 804 of the process 800. The image analysis circuit 2340 is further configured to determine the local brightness values of the respective zones 2110 based on the APLs of the filtered image parts in a manner similar to that performed in step 806 of the process 800. The image analysis circuit 2340 is further configured to forward the local brightness values generated for the respective subzones 120 or the respective zones 2110 to the 2D RAM 2350. The 2D RAM 2350 is configured to store the local brightness values generated for the respective subzones 120 or the respective zones 2110 and to sequentially forward the stored local brightness values to the 1D module 2360. The 1D module 2360 is configured to be responsive to a 1D/2D select signal for processing the local brightness values received from the 2D RAM 2350. The 1D/2D select signal indicates whether the display driver 2300 is in a 1D mode or 2D mode. The 1D mode is an operation mode in which the display driver 2300 is used in the panel display device 1000 that includes the 1D backlight device 200. The 2D mode is an operation mode in which the display driver 2300 is used in the panel display device 2000 that includes the 2D backlight device 2200. The 1D module 2360 is configured to generate, when the display driver 2300 is in the 1D mode, the base backlight values for the light sources 210 in a manner similar to that performed by the 1D module 1360 described in relation to FIG. 12. The 1D module 2360 is further configured to output, when the display driver 2300 is in the 2D mode, the local brightness values determined for the respective zones 2110 as the base backlight values for the respective light sources 2210 without modification. More specifically, in the 2D mode, the local brightness value determined for a zone 2110 of interest is used as the base backlight value for the light source 2210 corresponding to that zone 2110 without modification.

FIG. 19 shows an example configuration of the 1D module 2360, according to one or more embodiments. The 1D module 2360 is configured similarly to the 1D module 1360 shown in FIG. 13, except that the 1D module 2360 further includes a selector 2380 configured to select the output of the 2D RAM 2350 and the output of the flipflop FF3 1356 in response to the 1D/2D select signal. When the 1D/2D select signal indicates that the display driver 2300 is in the 1D mode, the selector 2380 selects the output of the flipflop FF3 1356. In this case, the base backlight value of each light source 210 is determined to be equal to the maximum value of the averaged local brightness values calculated for the zone 110 corresponding to that light source 210. When the 1D/2D select signal indicates that the display driver 2300 is in the 2D mode, the selector 2380 selects the output of the 2D RAM 2350. In this case, the base backlight value for each light source 2210 is determined to be equal to the local brightness value of the zone 2110 corresponding to that light source 2210.

Referring back to FIG. 18, the backlight value generation circuit 2370 is configured to generate the backlight values for the respective light sources 210 of the 1D backlight device 200 or the respective light sources 2210 of the 2D backlight device 2200 by modifying the base backlight values based on the DBV. In implementations where the backlight value generation circuit 2370 stores demura data,

the backlight value generation circuit 2370 may be configured to modify the base backlight values for the respective light sources 210 or 2210 further based on the demura data to mitigate display mura.

The configuration of the display driver 2300 shown in FIG. 18, which is adapted to both of the 1D backlight device 200 and the 2D backlight device 2200, effectively improves the usability of the display driver 2300.

The use of the terms “a” and “an” and “the” and “at least one” and similar referents in the context of describing the invention (especially in the context of the following claims) are to be construed to cover both the singular and the plural, unless otherwise indicated herein or clearly contradicted by context. The use of the term “at least one” followed by a list of one or more items (for example, “at least one of A and B”) is to be construed to mean one item selected from the listed items (A or B) or any combination of two or more of the listed items (A and B), unless otherwise indicated herein or clearly contradicted by context. The terms “comprising,” “having,” “including,” and “containing” are to be construed as open-ended terms (i.e., meaning “including, but not limited to,”) unless otherwise noted. Recitation of ranges of values herein are merely intended to serve as a shorthand method of referring individually to each separate value falling within the range, unless otherwise indicated herein, and each separate value is incorporated into the specification as if it were individually recited herein. All methods described herein can be performed in any suitable order unless otherwise indicated herein or otherwise clearly contradicted by context. The use of any and all examples, or exemplary language (e.g., “such as”) provided herein, is intended merely to better illuminate the invention and does not pose a limitation on the scope of the invention unless otherwise claimed. No language in the specification should be construed as indicating any non-claimed element as essential to the practice of the invention.

Exemplary embodiments are described herein. Variations of those exemplary embodiments may become apparent to those of ordinary skill in the art upon reading the foregoing description. The inventors expect skilled artisans to employ such variations as appropriate, and the inventors intend for the invention to be practiced otherwise than as specifically described herein. Accordingly, this invention includes all modifications and equivalents of the subject matter recited in the claims appended hereto as permitted by applicable law. Moreover, any combination of the above-described elements in all possible variations thereof is encompassed by the invention unless otherwise indicated herein or otherwise clearly contradicted by context.

The invention claimed is:

1. A display device, comprising:

a backlight device comprising a plurality of light sources configured to illuminate a plurality of zones of a display panel, respectively, the plurality of zones being aligned in a first direction, each of the plurality of zones comprising a plurality of subzones aligned in a second direction perpendicular to the first direction; and a backlight control circuit configured to: receive an input image; and determine a backlight value for a target light source of the plurality of light sources, the target light source corresponding to a target zone of the plurality of zones; wherein determining the backlight value for the target light source comprises:

determining local brightness values of respective sub-zones of the target zone based on the input image; and

determining the backlight value for the target light source based on the local brightness values of the subzones of the target zone;

wherein determining the local brightness values of the respective subzones comprises:

selecting target parts of the input image for the respective subzones of the target zone;

filtering the target parts to generate filtered image parts for the respective subzones; and

determining the local brightness values of the respective subzones based on the filtered image parts.

2. The display device of claim 1, wherein the plurality of zones have a substantially rectangular shape that extends in the second direction; and

wherein the subzones have a substantially square shape.

3. The display device of claim 1, wherein determining the local brightness values of the respective subzones comprises:

calculating average picture levels (APL) of the respective filtered image parts; and

determining the local brightness values of the respective subzones based on the APLs.

4. The display device of claim 1, wherein filtering the target parts comprises applying filter coefficients to pixel luminance levels of pixels of the target parts of the input image:

wherein the filter coefficients applied to the pixel luminance levels of the pixels of a respective one of the target parts selected for a respective one of the subzones are defined depending on respective distances between the pixels of the respective one of the target parts and a center of the respective one of the subzones.

5. The display device of claim 1, wherein determining the backlight value for the target light source further comprises: averaging the local brightness values determined for respective combinations of two or more adjacent ones of the subzones to determine averaged local brightness values; and

determining the backlight value for the target light source based on the averaged local brightness values.

6. The display device of claim 5, wherein determining the backlight value for the target light source is based on a maximum value of the averaged local brightness values.

7. The display device of claim 1, further comprising: a light guide plate having a major surface attached to a rear surface of the display panel;

wherein the plurality of light sources is attached to a side face of the light guide plate.

8. A display driver, comprising:

a driver circuit configured to drive a display panel based on an input image, wherein the display panel is illuminated by a backlight device comprising a plurality of light sources aligned in a first direction and configured to illuminate a plurality of zones of the display panel, respectively, each of the plurality of zones comprising a plurality of subzones aligned in a second direction perpendicular to the first direction; and

a backlight control circuit configured to determine a backlight value for a target light source of the plurality of light sources, the target light source corresponding to a target zone of the plurality of zones;

wherein determining the backlight value for the target light source comprises:

19

- determining local brightness values of respective sub-zones of the target zone based on the input image; and
- determining the backlight value for the target light source based on the local brightness values of the subzones of the target zone; 5
- wherein determining the local brightness values of the respective subzones comprises:
- selecting target parts of the input image for the respective subzones of the target zone; 10
- filtering the target parts to generate filtered image parts for the respective subzones; and
- determining the local brightness values of the respective subzones based on the filtered image parts. 15
9. The display driver of claim 8, wherein the plurality of zones have a substantially rectangular shape that extends in the second direction; and
- wherein the subzones have a substantially square shape. 20
10. The display driver of claim 8, wherein filtering the target parts comprises applying filter coefficients to pixel luminance levels of pixels of the target parts of the input image; 25
- wherein the filter coefficients applied to the pixel luminance levels of the pixels of a respective one of the target parts selected for a respective one of the subzones are defined depending on respective distances between the pixels of the respective one of the target parts and a center of the respective one of the subzones. 30
11. The display driver of claim 8, wherein determining the backlight value for the target light source further comprises:
- averaging the local brightness values determined for respective combinations of two or more adjacent ones of the subzones to determine averaged local brightness values; and 35
- determining the backlight value for the target light source based on the averaged local brightness values. 40
12. The display driver of claim 11, wherein determining the backlight value for the target light source is based on a maximum value of the averaged local brightness values. 45
13. The display driver of claim 8, wherein the backlight control circuit comprises a memory configured to store the local brightness values of the respective subzones of the target zone.
14. The display driver of claim 13, wherein the driver circuit is further configured to drive a second display panel based on a second input image, the second display panel comprising a plurality of second zones arrayed in rows and columns, the plurality of second zones being illuminated by a plurality of second light sources, respectively; and 50
- wherein the backlight control circuit is further configured to:
- determine second local brightness values of the plurality of second zones, respectively, based on the second input image; 55
- store the second local brightness values in the memory; and
- determine second backlight values for the plurality of second light sources based on the second local brightness values.

20

15. A method, comprising:
- illuminating, by a display device comprising a plurality of light sources, a plurality of zones of a display panel, wherein the plurality of light sources respectively illuminate the plurality of zones, wherein the plurality of zones are aligned in a first direction, and wherein each of the plurality of zones comprises a plurality of subzones aligned in a second direction perpendicular to the first direction;
- receiving, by the display device, an input image; and
- determining, by the display device, a backlight value for a target light source of the plurality of light sources, the target light source corresponding to a target zone of the plurality of zones; 10
- wherein determining the backlight value for the target light source comprises:
- determining local brightness values of respective sub-zones of the target zone based on the input image; and
- determining the backlight value for the target light source based on the local brightness values of the subzones of the target zone; 15
- wherein determining the local brightness values of the respective subzones comprises:
- selecting target parts of the input image for the respective subzones of the target zone; 20
- filtering the target parts to generate filtered image parts for the respective subzones; and
- determining the local brightness values of the respective subzones based on the filtered image parts. 25
16. The method of claim 15, wherein the plurality of zones have a substantially rectangular shape that extends in the second direction; and
- wherein the subzones have a substantially square shape. 30
17. The method of claim 15, wherein determining the backlight value for the target light source further comprises:
- averaging the local brightness values determined for respective combinations of two or more adjacent ones of the subzones to determine averaged local brightness values; and 35
- determining the backlight value for the target light source based on the averaged local brightness values. 40
18. The method of claim 17, wherein determining the backlight value for the target light source is based on a maximum value of the averaged local brightness values. 45
19. The method of claim 15, wherein determining the local brightness values of the respective subzones comprises:
- calculating average picture levels (APL) of the respective filtered image parts; and
- determining the local brightness values of the respective subzones based on the APLs. 50
20. The method of claim 15, wherein filtering the target parts comprises applying filter coefficients to pixel luminance levels of pixels of the target parts of the input image; 55
- wherein the filter coefficients applied to the pixel luminance levels of the pixels of a respective one of the target parts selected for a respective one of the subzones are defined depending on respective distances between the pixels of the respective one of the target parts and a center of the respective one of the subzones.
